UNITED STATES PATENT OFFICE.

CHARLES HEDENBERG YOUNG, OF NEW YORK, N. Y.

DESIGN FOR A SADDLE FOR BICYCLES, &c.

SPECIFICATION forming part of Design No. 25,030, dated December 31, 1895.

Application filed November 16, 1895. Serial No. 569,231. Term of patent 14 years.

To all whom it may concern:

Be it known that I, CHARLES HEDENBERG YOUNG, of New York city, in the county and State of New York, have invented and produced a new and original Design for Bicycle and like Saddles, of which the following is a full, clear, and exact description.

Reference is to be had to the accompanying drawings, forming a part of this specification, in which similar characters of reference indicate corresponding parts in all the views.

Figure 1 is a perspective view of a bicycle-saddle embodying my new design. Fig. 2 is a plan view of the saddle. Fig. 3 is a longitudinal section taken on a line corresponding to the line 33 of Fig. 2, and Figs. 4 and 5 represent cross-sections taken respectively on lines 44 and 55 of Fig. 2.

The leading feature of my design consists in a saddle that is prolonged in narrowed form forwardly, the upper surface presenting in its rear a broadened portion, and a longitudinal depression which ranges lengthwise of the saddle, the bottom surface of the depression merging into the higher surface of the seat.

A more specific description of the design in all its details follows, the different elements making up the novel conformation being designated by terms suggested by the corre-

sponding portions of the human body. Thus 30 the saddle represents a transverse sacral curve *a* and the right and left thigh curves *b b*, which merge posteriorly into the sacral curve *a* and conjoin anteriorly, forming the pommel *c*. The top surface of the saddle 35 curves over the edge and merges into the side surfaces.

a is the sacral curve and surface; *b b*, the left and right thigh curves and surfaces, joining posteriorly with the sacral curve and conjoining anteriorly to form *c*—the pommel; *d*, the cantle-ridge over the sacral curve; *e e*, the left and right buttock surfaces, corresponding to the buttocks; *f*, the perineal concavity, corresponding to the convexity of the 45 perineum, extending from a point between the buttock-surfaces anteriorly to the end of the pommel. Bordering said depression *f* at the sides are the perineal ridges *g g* from *c* to *d*, the antero-posterior surface diameter. 50

I claim—

The design for a bicycle or like saddle herein shown and described.

CHARLES HEDENBERG YOUNG.
